PACKAGE

William J. McDonald, Brooklyn, N. Y., assignor
to Pecheur Lozenge Company, Inc., Brooklyn,
N. Y., a corporation of New York

Application August 25, 1938, Serial No. 226,796

3 Claims. (Cl. 99—180)

This invention relates to packages, and has for its particular object the provision of a convenient package for small objects, such as candy lozenges. A further object of the invention is to provide a package which can readily be assembled so as to afford convenient inspection of the contents displaying the goods in an attractive manner to the best advantage.

A still further object of the invention is to provide a candy package in which the candy is wrapped in rolls and the rolls are assembled together in a package which may stand erect on the sales counter, being supported by an insert member which may be taken out and discarded when the package is opened for the first time, leaving the outer transparent wrapper as a complete bag which provides sanitary protection for either all the contents, or for such of the contents as may remain.

20 In the drawing:

Figure 1 is a front view of my improved package in its preferred form.

Figure 2 is an end view of the same.

Figure 3 is a top plan view.

25 Figure 4 is a view of the bag or container after removal of the insert member.

Figure 5 is a view of the insert member.

In the preferred form of the invention six to a dozen or more of the candy disks 10 are placed 30 with their flat sides together to form a cylindrical roll which is then wrapped in transparent paper 12, preferably crimped at the ends as at 13. The wrapper 12 is not an essential part of my invention and may be omitted in which case 35 the rolls can be held in place by the insert member, which may be an elongated strip of material having a central panel 15 and two end panels 16, the strip being of uniform width equal to the diameter of the candy disks. The ends of 40 the insert, when used with disks, are each semi-circular as shown at 17. The scoring 18 of the insert member provides a central panel of exactly the length of each roll or stack and the right angularly bent ends are of such length as to 45 accommodate the desired number of rolls.

When the rolls, here shown as three in number, are assembled with the card insert they are covered with a strip of transparent material 20, which at its central portion engages the top roll 50 and the two semi-circular ends 17 of the insert member. The sides of the transparent sheet are now, or previously, sealed together permanently to form a bag but are not secured in any way to the insert member.

55 The sealing of the sides of the outside wrapper

extends to the top portion of the insert, which is the central panel 15, and preferably to the top of the bag, as shown. The short sides 21 are now folded down against the top panel 15 of the insert member, leaving two trapezoidal end flaps. 5 The folded shorter end flap 25 is now turned in upon and over the exposed surface of the central panel of the insert member and protects this member, but it is not in any way secured to it. The folded longer end flap 26 is 10 now sealed to the shorter end flap 25 and in the preferred form, this longer end flap 26 projects beyond the package as at 27, forming a tab which may readily be grasped to open the package.

15 While I prefer to wrap each roll or stack separately with transparent material and I prefer to use an outer wrapper entirely of Cellophane, which is now made by a number of manufacturers, the word "transparent" in the claims is 20 not to be interpreted as limiting the material to Cellophane because either for the roll wrapping or the outer wrapping I may use a material which is opaque in part but is transparent in the center. The sealing may be done in any 25 preferred manner, but preferably by a heat application rather than by the use of an adhesive.

The insert, as stated, is entirely independent 30 of the outer wrapping which is a full and complete bag having a rounded bottom when the material is disk-shaped. The insert member has a number of functions: it facilitates the making of the package; it maintains the shape 35 of the package during shipment; and it permits the complete display of the entire package in a most attractive manner as the central panel forms a support for the package which in the absence of the central panel would fall over if placed with the axes of the rolls extending 40 horizontally in a vertical plane as is preferred. In the preferred form the candies are disk lozenges and each and every tablet of candy is visible from each of the two sides of the package when the package is being displayed on a 45 counter and rests upon the central panel of the insert member which is preferably opaque and serves to carry advertising matter or descriptive matter or both. The pieces may not be candy and may be other than round in side elevation, 50 square for example, as mints.

In using the package after purchase, the tab 55 27 is gently pulled, unsealing the two end flaps 25 and 26 without destroying either. The insert is now removed and may be discarded. The top

roll can conveniently be removed and the transparent bag or container remains intact so that the remaining contents may be carried conveniently in the bag, which is now reduced in bulk 5 and weight and forms a sanitary protection for the remaining contents.

I am familiar with packages including a cardboard tray with a transparent covering glued to or otherwise permanently secured to the cardboard but in all these cases the cardboard portion 10 is a permanent part of the package whereas in the present device the insert, preferably opaque and of cardboard, is entirely free of the bag and is discarded just as soon as the package is first 15 opened, having then served its multiple functions.

What I claim is:

1. A candy package comprising a plurality of rolls of candy wrapped as cylinders in transparent coverings with their axes in a single plane, a member having a central panel fitting along an edge of one roll and having two end panels covering the ends of all of the cylindrical rolls, the width of the member being uniformly the same 25 as the diameter of the candy rolls and its two ends being semi-circular, a transparent sheet covering snugly the member and the rolls having its sides closed upon themselves to form a bag with a rounded bottom, one end of the sheet being folded over the central panel of the member and the other end being sealed to said one end, whereby upon pulling said other end the bag may be unsealed and the member may readily 30

be removed to give access to the top roll, said member serving to strengthen the package, form a support so that the package may stand erect as for display, and upon first use of the package may be discarded to reduce weight and bulk of the package which remains as a bag affording sanitary protection to the remaining rolls. 5

2. A candy package comprising a plurality of rolls of candy disks, a transparent bag of size to receive snugly the plurality of rolls, an insert 10 having two bent end portions covering the ends of all the rolls, the central panel of the insert between the two end portions conforming to the longitudinal cross section of a roll and being covered by the closed end of the bag but not secured thereto, whereby when the bag is opened the insert may be removed with or without the upper roll of candy, leaving the bag for reuse with the remaining rolls. 15

3. In combination, a transparent bag having a rounded bottom and a rectangular transverse cross section throughout the greater part of its length, and a stiffening insert having a central panel conforming to said cross-section with its two ends extending in the direction of the rounded bottom of the bag, the ends of the bag being closed on itself above and free of the central panel so that the insert may readily be removed when the bag is opened, said central panel serving as a bottom upon which the bag may stand in an inverted position when exposed for sale. 20 25 30

WILLIAM J. McDONALD.
